DESIGN FOR A STORAGE BATTERY CELL
COVER

Charles L. Keller, Cincinnati, Ohio, assignor to
The Richardson Company, Lockland, Ohio, a
corporation of Ohio

Application March 27, 1935, Serial No. 56,080

Term of patent 7 years

To all whom it may concern:

Be it known that I, Charles L. Keller, a citizen of the United States, residing in Cincinnati, in the county of Hamilton and State of Ohio, have invented a new, original, and ornamental Design for Storage Battery Cell Covers, of which the following is a specification, reference being had to the accompanying drawing forming a part thereof.

In the drawing:

Figure 1 is a top perspective view of a storage battery cell cover embodying my new design.

Fig. 2 is a bottom perspective view of the same.

Fig. 3 is an enlarged fragmentary section of the upper corner of Fig. 1, more clearly illustrating the type of ornamentation.

The dominant features of the design herein claimed are the random spaced crater-like projections on the top of the cell cover, being illustrated in the drawing in solid lines.

I claim:

The ornamental design for a storage battery cell cover as shown and described.

CHARLES L. KELLER.
